UNITED STATES PATENT OFFICE

BRODDE E. F. RHODIN, OF ATLANTIC CITY, NEW JERSEY.

ELECTROLYTIC SEPARATION.

Application filed May 26, 1922. Serial No. 563,763.

To all whom it may concern:

Be it known that I, BRODDE E. F. RHODIN, a subject of the King of Great Britain, and a resident of Atlantic City, county of Atlantic, and State of New Jersey, have invented certain new and useful Improvements in Electrolytic Separation, of which the following is a specification.

This invention relates to the art of electrolytic decomposition or separation such as practised in the manufacture of magnesium, sodium and potassium.

One of the problems experienced in such work has been to effect a practical separation of the products released at the anode and cathode and to prevent a re-combination of the same. Various expedients have been proposed. In the earlier forms a solid diaphragm of insulating material was interposed between the electrodes and the action took place about the lower edge of such barrier. This structure was modified by providing straight passages therethrough. This modification reduced the mechanical and electrical resistance, but as with the former did not prevent re-combination. By a further modification the passages were sloped downwardly, away from the anode side of the partition to prevent outflow of the gases but this construction offered no check to the inflow of material released at the cathode and so did not prevent re-combination of the elements. Porous diaphragms also have been proposed, but these are inefficient because of their high mechanical and electrical resistance, necessitating the use of higher voltages than are desirable.

The objects of my invention are to overcome the present difficulties in the art, including those above enumerated, and to effect a free decomposition and complete or substantially complete separation, without re-combination; and further, to accomplish the same with low voltage and relatively high ampere hour efficiency.

The foregoing and other objects are attained in my invention by certain novel features of construction, combination and relation of parts, as will be clear from the following specification, which is to be read in conjunction with the drawings accompanying and forming part of the same.

Figure 1 in the drawings referred to is

a plan view of an electrolytic cell constructed in accordance with and embodying features of the invention.

Figure 2 is a vertical sectional view of the same as taken on substantially the plane of line 2—2 of Figure 1.

Figure 3 is a horizontal sectional view as taken on substantially the plane of line 3—3 of Figure 2.

Figure 4 is an enlarged broken sectional view illustrating a modified sectional construction of the partition which in this case is cylindrical in form to surround a centrally located anode.

Figures 5 and 6 are plan and vertical sectional views respectively of another form of the invention, in which the body of the cell is of metal and itself forms the cathode.

In the form of the invention first shown, the electrodes consist of a centrally located anode 7 surrounded by a series of cathode elements 8, all being mounted in the insulating support 9 constituting a cover to the vessel 10, which is constructed to contain the fused electrolyte.

In the case of magnesium separation, the electrolyte usually consists of a bath of mixed chlorides of magnesium and potassium or magnesium, potassium and sodium maintained in properly fused condition. This bath is kept substantially constant by supplying magnesium chloride, as required, the anode in the present disclosure being constructed for this particular purpose by providing it with a feed passage 11 therethrough, terminating at the lower end in a series of slots 12 forming distributing channels.

Interposed between the electrodes of opposite polarity is a barrier or partition 23 of non-conducting material such as alundum or the like, this barrier in the present disclosure taking the form of a cylinder surrounding the anode and thereby forming within the cell outer and inner concentric chambers.

In the example under discussion, where magnesium is being produced, the magnesium is released in the outer chamber and the chlorine is released in the inner chamber, the first in the form of a metal and the second in the form of a gas. The bath being of greater specific gravity, both these elements will rise to the surface, the mag-

nesium collecting and being removed ordinarily from time to time and the gas being suitably conducted away.

For efficient operation the electrolyte should have free access to the electrodes of opposite polarity. To allow for this and at the same time hold apart the elements liberated at the cathode and anode, the partition is constructed with electrolyte passages therethrough, each having a dip or depression intermediate the opposite ends of the same to thereby provide positive stops against the flow of lighter materials from both sides of the partition. In the present illustrations these electrolyte passages are of substantially V-shape as shown at 13, with sharply angled end portions inclined downwardly from the opposite sides of the partition. These sharp downward bends, it will be seen, offer no impedance to the electrolyte, but do oppose and prevent the lighter materials passing therethrough. The chlorine gas, in the example under consideration, is thus trapped within the cylindrical inner chamber and the magnesium metal is in the same fashion caught and held within the outer chamber.

The number and size of the electrolyte passages may vary to suit different conditions. As an example I have shown in Figure 4 how these passages may be in the form of arcuate slots extending partly about the periphery of the cylinder. Also in the figure referred to I have shown how the cylinder may be made up in cylindrical sections 14, set one on top of the other, formed at their upper edges with trough-like grooves 15 and at their lower edges with corresponding pointed projections 16 cooperating when the units are assembled to form the electrolyte passages, substantially V-shaped in cross section. To position these units so that the intermeshing parts described will properly register to form the passages, I have shown them as having cooperating tongue and groove engagement, as indicated at 17.

To facilitate removal of the collected material from the outer chamber I have shown the cover as having a removable section 18 and the escape of the gas from the inner chamber is here provided for by constructing the anode with a gas outlet passage 19.

The containing vessel is shown in Figure 2 as constructed with a centrally located well 20 for the collection of impurities, this well being closed in by the cylindrical partition which is shown as resting upon the bottom of the vessel about the periphery of this well.

The structure of Figures 5 and 6 is generally similar to that described, the main distinction being that the containing vessel is made of metal and used as the cathode electrode, it having a suitable terminal 21,

by which the necessary electrical connections can be made thereto. Also in this case the collection well 20 is provided in the bottom of the vessel by placing the lowermost electrolyte passages in the partition a sufficient distance above the lower end of the same to form a substantial chamber, the bottom of which may be provided by an insulating block 22 on which the cylinder rests.

With this invention because of the greater freedom and accessibility of the electrolyte to both electrodes good conductivity is provided, the electrical resistance is reduced to a minimum and consequently, the cell can be operated at much lower voltage than has heretofore been practicable. Also there are no losses due to recombination and hence the cell can be operated at high ampere hour efficiency and consequently, with relatively low power consumption. 85

What I claim is:

1. In electrolytic separation, an electrolytic cell having electrodes of different polarity separated by a partition of insulating material constructed with electrolytic passages therethrough, each inclined upwardly at its opposite ends to hold back the lighter products released at the different electrodes. 90

2. In electrolytic separation, an electrolytic cell having electrodes of different polarity separated by a partition of insulating material constructed with an electrolytic passage therethrough with a downwardly offset portion intermediate the ends of the same to hold back the lighter products at 100 both sides of the partition.

3. In electrolytic separation, an electrolytic cell having electrodes of opposite polarity and an insulating barrier separating said electrodes and provided with passages therethrough, each formed with a dip intermediate the ends of the same so as to hold back the lighter products at both sides of the barrier.

4. An electrolytic cell having electrodes separated by a partition of insulating material formed with substantially V-shaped passages therethrough having sharply inclined reversely sloping portions for holding back the lighter products at opposite sides of the partition. 110

5. In electrolytic separation of elements in a fused electrolyte, wherein such elements are of lower specific gravity than the electrolyte, an electrolytic cell having electrodes of different polarity separated by a non-conductor partition having means for separating and preventing recombination of the products of decomposition and for providing low resistance conductivity between the electrodes within the field of decomposition. 115

6. In electrolytic separation, a fused bath of greater specific gravity than the elements which are to be decomposed therein, 120

electrodes of different polarity entered in said bath and a partition of insulating material between said electrodes having electrolyte passages therethrough provided with means for preventing flow therethrough in either direction of the lighter products present at the opposite sides of such partition.

7. The herein disclosed process of electrolytic separation which includes maintaining a bath of fused electrolyte substantially continuously between an anode and cathode and at the same time separating and preventing recombination of the final products of electrolysis.

8. The herein disclosed process of electrolytic separation which includes maintaining a bath of fused electrolyte in continuous communication between electrodes of opposite polarity while separating and

preventing re-combination of the final products of electrolysis.

9. In an electrolytic cell, a partition of insulating material consisting of built-up sections resting one on the other and formed at their adjacent edges with parts providing passages therethrough.

10. The structure of claim 9 in which said passages each have oppositely inclined end portions.

11. An electrolytic cell having electrodes of opposite polarity and a barrier of aluminum separating said electrodes but provided with electrolytic passages therethrough each formed with a dip intermediate the ends of the same so as to hold back the lighter products at both sides of the barrier.

In witness whereof, I have hereunto set my hand this 18th day of May, 1922.

BRODDE E. F. RHODIN.
